UNITED STATES PATENT OFFICE.

LUIGI PIGNANELLI, OF TACOMA, WASHINGTON.

SHOE.

REISSUED

Application filed August 17, 1926. Serial No. 129,703.

This invention relates to shoes and, more especially, to that class known as "turned" shoes.

The object of my invention, generally stated, is to provide a light weight shoe which will retain its shape, be more comfortable to wear, stronger, and more durable than hitherto.

More specific objects and advantages of the invention will appear in the following description.

The invention consists in the novel manner of shaping a shoe upper or vamp and in the method of connecting the same to the sole, as will be hereinafter described and claimed.

In the accompanying drawings,—

Figure 1 is a plan view of parts of a turned shoe embodying my improvements, the shoe upper being illustrated as lasted and sewed to the sole; Fig. 2 is a similar view with the flaps of the upper joined together above the sole; Fig. 3 is a transverse sectional view on line 3—3 of Fig. 1; Fig. 4 is a transverse sectional view on line 4—4 of Fig. 2; Fig. 5 is a fragmentary perspective view of the shoe illustrated in Figs. 2 and 4 as it appears when turned right side out; Fig. 6 is a fragmentary sectional view of a shoe turned right side out, wherein the meeting ends of the upper's flaps are shown as scarfed with respect to each other; Fig. 7 is a transverse sectional view of a welt shoe embodying the invention; Fig. 8 is an expanded view of an upper shaped according to the present invention; and Fig. 9 is a view similar to Fig. 6 showing the invention as employed with a vamp.

In carrying out the invention, a shoe upper, as 10, is shaped to provide in a single piece two complementary flap elements 11 and 11¹ extending from opposite sides of a vamp portion 10¹ of a full upper (Fig. 8) or of a vamp upper 10², as shown in Fig. 9.

Longitudinally of the upper said flaps are disposed in proximity to its toe end 12 and of a width to extend to the rear of the ball part of the shoe.

Transversely of the upper, said flaps are of lengths to enable them, when the upper is lasted, to have their free ends joined together at, or in proximity to, the midwidth of the sole.

In applying my invention to a turned shoe, the shoe sole 13, after being shaped and channeled, is temporarily secured by means of tacks to a last 14 with the grain side of the

leather, or the surface which is to serve as the bottom, next the last as usual with a turned shoe. My improved upper as 10 (or 10², Fig. 9) is then placed, wrong side out, about the last to have the edges of the upper overlap the edge of the sole 13 and to which it is sewed, the stitches being indicated by 16 and 16¹; the stitches 16¹ extending across those parts of the upper proper (Figs. 1 and 3) from which the flaps protrude. The flaps are then turned down upon the sole to have their free ends meet or nearly so.

In Figs. 2 and 4 the outer or free ends of the flaps are shown in side by side relation and, thus arranged, are coupled together, preferably by means of flexible strips 18 and 18¹ which are glued or cemented to the under and upper surfaces, respectively, of the flaps. A strip which is found to be suitable for joining the flaps is afforded by what is known as adhesive tape—that is to say, a fabric strip having an adhesive material applied to one surface thereof.

In practice the flaps' front and rear edges are chamfered as at 20 and 20¹ to eliminate sharp corners; and the edges of the flaps to which the joining strips are applied is advantageously chamfered, as at 23, to compensate for the thickness of said strips.

In Fig. 6 the flaps are shown as joined without the use of strips, by elongating the flaps, transversely, of the shoe and cementing, as at 19, the overlapping chamfered portions of the flaps together.

After the upper has been sewed to the sole and the flaps secured to each other, as above explained, the last 14 is taken out. The shoe is then turned right side out and the last reinserted preparatory to hammering or otherwise bringing the shoe into proper form.

In Fig. 7 I illustrate the invention as applied to a welt shoe, wherein 24 represents the welt which is sewed as by stitches 16² to the flaps 11, 11¹, or to the vamp 10¹ proper in proximity to the respective flaps, the sole 25 being sewed in the usual manner to said welt. Beside the sewing of an upper by stitches 16 and 16¹ to the shoe sole it may be further secured by cementing the flaps directly to the sole.

According to my invention a shoe is provided with a bridge piece, see Figs. 5, 6 and 7, constituted of the upper's companion flaps 11 and 11¹ which are joined together and extend across the sole at the ball thereof and serve as a tie to couple the opposite sides of

the vamp together supplementary to their sewed connection 16¹ with the sole. It is to be noted that in the present invention, the flap elements 11 and 11¹ are not sewed or otherwise secured to the vamp of the upper, but are integral therewith—that is to say, an upper, or vamp, is shaped of a single piece to afford the flaps.

By such construction dependence is not had upon the strength of the stitches to hold the flaps to the upper. Moreover, flaps co-extensive with the vamp at the ball obviates the presence of ridges which would chafe or bruise the foot.

It is to be noted that the stitches 16¹ serve to secure the vamp or upper to the sole, but the flaps which are secured to each other and to the sole, if desired, serve to prevent the spreading apart of the lower side portions of the vamp or the breaking away transversely of the latter from the sole when the shoe is strained or subjected to walking stresses. With the present invention a relatively thin sole and insole may advantageously be employed to afford a lightweight shoe which is especially desirable with women's wear.

What I claim, is,—

1. In a shoe, an upper shaped to provide in a single piece with the vamp side flaps which are adapted to be turned inwardly above the sole, the free ends of the flaps being secured together, said upper being sewed to the sole by means of stitches disposed in spaced apart relation to the respective flaps.

2. In a shoe, a sole, an upper, said upper being shaped to provide two complementary flap elements disposed in spaced apart relation with respect to both ends of the upper, and adhesive tape for securing the free ends of the flaps together, said upper being secured to the sole by stitches disposed in spaced apart relation from the respective flaps.

3. A shoe upper having a flap element coextensive with and protruding laterally from each side of the vamp, said vamp being sewed to the sole by means of stitches located in spaced apart relation to the respective flaps, and a means for adhesively coupling the flaps together.

Signed at Seattle, Washington, this 12th day of July, 1926.

LUIGI PIGNANELLI.
